CLAIM

The ornamental design for an audio player, as shown and described.

DESCRIPTION

The patent or application file contains at least one drawing executed in color. Copies of this patent or patent application publication with color drawing(s) will be provided by the Office upon request and payment of the necessary fee.

1. Audio player

1.1 : Perspective

1.2 : Front

1.3 : Back

1.4 : Left

1.5 : Right

1.6 : Top

1.7 : Bottom

The broken lines shown in the figures depict portions of the audio player that form no part of the claimed design. The portions of the audio player shown in the color yellow form no part of the claimed design.

1 Claim, 7 Drawing Sheets

(5 of 7 Drawing Sheet(s) Filed in Color)
